SIGN

Otto W. Harms, Chicago, Ill.

Application April 26, 1937, Serial No. 138,907

2 Claims. (Cl. 40—32)

This invention relates to signs. One of the objects of the invention is to provide a sign in which the display travels or is stationary and having novel features which tend to attract and arrest the attention of passersby. Another object is to provide a sign in which the letters or characters are transparent, whereas, the remainder of the face of the sign is opaque, whereby when the sign is illuminated from behind, the letters and characters forming the display will be perfectly clear, distinct and legible in the dark as well as in the light. Another object is to provide a sign with plate supporting members having spaced openings therein for the reception of plates which have cut-out portions outlining the letters or characters or are made transparent, and the surface portion thereof made opaque around outlines which define letters or characters. Another object is to provide a sign in which the character displaying plates are carried by a belt contained in a case and propelled by suitable means to pass by a sight opening in the front of the case, whereby a relatively long legend may be presented to persons looking at the sign. Another object is to provide character displaying plates which may pass around rollers or other belt carrying means. Another object is to provide means whereby the gaps between adjacent character displaying plates are covered so as to prevent any light from passing through the gaps between adjacent edges of the plates.

Other objects and advantages will appear in the course of this specification and, with all of said objects and advantages in view, this invention consists in the several novel features of construction, arrangement and combination of parts hereinafter fully set forth and claimed.

The invention is clearly illustrated in the drawings accompanying this specification in which:

Fig. 1 is a front elevation of a sign embodying one form of the present invention.

Fig. 2 is a horizontal section therethrough.

Fig. 3 is a detail, enlarged, fragmental front elevation of the plate carrying belt illustrated in Figs. 1 and 2.

Fig. 4 is a detail, enlarged, vertical cross-section taken on the line 4—4 of Fig. 3.

Fig. 5 is a detail, enlarged horizontal section taken on the line 5—5 of Fig. 3.

Fig. 6 is a front elevation of a fragment of a modified form of plate carrier and illustrates two of the character displaying plates associated with said form of carrier.

Fig. 7 is a plan of the plates illustrated in Fig. 6.

Fig. 8 is a front elevation of a modified form of the invention.

Fig. 9 is an enlarged, vertical cross-section taken on the line 9—9 of Fig. 8.

Fig. 10 is a detail, enlarged, fragmental front elevation of the display plate support illustrated in Fig. 8.

Fig. 11 is a detail, vertical cross-section taken on the line 11—11 of Fig. 10.

Fig. 12 is a detail, horizontal section taken on the line 12—12 of Fig. 10.

Fig. 13 is a detail, enlarged front elevation of one of the character display plates.

Fig. 14 is a horizontal cross-section taken on the line 14—14 of Fig. 13.

Referring to said drawings and first of Figs. 1 to 5 inclusive, which illustrate the invention applied to a sign in which the character displaying plates travel, the reference character 16 designates a rectangular case of any suitable construction, formed with a sight opening 17 in its front wall 18. Rotatively mounted in said case adjacent each end thereof are rollers 19, 20 and 19^a, 20^a, the rollers 19 being arranged in pairs as shown, and the rollers 20 being disposed intermediate those of the pairs. The rollers 19^a, 20^a are disposed diagonally opposite each other at two corners of the case. Trained around said rollers is an endless belt 21 which carries the character displaying plates 22 and propels said plates along the sight opening in the front wall of the case where they are exposed to view. One of the rollers, as for example the one designated by 19^a, is a driving roller and is rotated by a motor 23 which may be in the form of a spring motor, an electric motor or other power device.

In Fig. 2 the belt 21 is shown diagrammatically. One or more electric light bulbs 24, or any other source of illumination, is placed behind that part of the belt which passes by the sight opening, and reflectors 25 may be employed in connection with the electric light bulbs to direct the rays of light towards the sight opening in the front wall of the case, whereby the transparent letters or characters formed in or by the plates 22 may be made perfectly legible and distinct in the dark as well as the light.

The belt 21 is desirably composed of two closely spaced flexible upper bands 26 and a flexible lower U shaped band 27 (see Figs. 3 and 4) connected by upright plate spacing members 28. The bands and spacing members may be composed of leather or other suitable belting so as to enable the belt to pass around the rollers, and the character displaying plates are flexible.

so that they may pass around the rollers. The upright plate spacing members 28 are desirably H shaped in cross-section as seen in Fig. 5, and each may be composed of two short strips secured together along their median lines by a row of stitches 29, which stitches may also be used to fasten the plate spacing members 28 to the bands 26, 27. The bands and plate spacing members provide rectangular spaces 30 in which are received the character displaying plates 22, which may be slid down through the slots between the bands 26 and down through the grooves in the plate spacing members 28, bringing the lower edge portions of the plates into the groove formed 15 in the U shaped lower band 27.

The character display plates may be constructed in various ways. For instance, the bodies 31 thereof may be made of thin flexible sheet metal, cardboard or the like as shown in Fig. 3 and the body of each plate may be cut out to define a letter or other character as at 32. To the rear face of the body 31 is adhesively secured a thin, transparent sheet 33^x, such as Cellophane, and it may have any desirable color. An assortment 25 of character display plates containing the various letters of the alphabet, digits, etc. may accompany each sign so that the user thereof may readily set up any display matter which is particularly desirable for advertising his goods.

Between the words displayed, opaque plates 33 are placed in the belt so as to prevent light from passing through the spaces between the plates that display the words. The plate spacing members 28 and opaque plates 33 exclude all light except that which passes through the transparent letters or characters, thereby preventing any unpleasant streaks of light to escape through the sight opening at the front of the case.

In Figs. 6 and 7 a fragment of a link belt 21^a is shown, and in this form of invention the links are provided with upwardly extended socket members 21^b adapted to receive tongues 22^b formed upon the lower edges of the character displaying plates 22^a. These plates, like the plates 22, have opaque surfaces formed with transparent portions 32^a which define the outlines of the letters of the alphabet or other characters, and the body portion of each plate is formed with a flap 34 along one edge that extends 50 over the adjacent edge of the adjacent plate to cover the gap therebetween so as to prevent any light from passing through the gap between the plates. In this form of plate the body may be formed of glass or other transparent material 31^b and the outline of the character may be formed by painting the surface of the body around the outline of the letter or character as at 33^c so as to leave that part transparent.

In the form of the invention illustrated in Figs. 60 8 to 14 inclusive, the invention is shown as applied to a stationary sign. In this form a rectangular frame 16^a is provided and in said frame is supported a stationary plate holding member 35. Said member is desirably composed of 65 several sets of upper and lower spaced strips 26^a, 27^a, each set being connected by upright plate spacing H bars 28^a soldered or otherwise rigidly

secured at their ends to the strips 26^a, 27^a. Between above and below the sets of strips are strips or sheets 36 extending the entire length of the frame and serving to exclude light from the spaces between the several rows of letters. The sheets 36 may be soldered to or may form part of the rear strips 27^a and the forwardly disposed strips 27^a have their lower edges secured to the rear strips 27^a or to the sheets 36 so as to provide grooves for the reception of the lower ends of the character displaying plates as in the other form hereinbefore described. 5 10

The sign is made up by placing the letters, which form words, in the spaces between the plate spacing bars 28^a and as in the other form 15 described, and opaque plates 33 are placed in the unoccupied spaces so as to prevent the light from passing through said spaces. In this form of the invention the character displaying plates 22^c may be formed of opaque material having 20 cut-out portions to define transparent letters and transparent colored or clear thin sheets 33^c, such as Cellophane or the like, are adhesively secured to the rear sides of the bodies of the plates (see Figs. 13 and 14). 25

This form of invention may be supported in show windows or wherever desired, and the light issuing from illuminating fixtures within the store may be used to illuminate the sign from behind, or, if desired, electric light bulbs and reflectors may be placed behind the sign, as in the form of the invention first above described. 30

With either form of sign, the display may be changed as often as is found desirable. Thus in effect a different sign may be presented daily or 35 as often as required.

From the above it is apparent that a very interesting sign is provided which attracts the attention of passersby. It may be made especially attractive by employing colored, transparent back- 40 ing behind the cut-out portions of the character display plates.

I claim as new and desire to secure by Letters Patent:

1. A sign comprising a pair of horizontal plate 45 holding members, a grooved plate holding member therebelow, upright grooved plate spacing members extending between and secured to said upper and lower plate holding members, character displaying plates removably held in the spaces 50 between said members, said plates having opaque surface portions outlining transparent portions defining characters.

2. A sign comprising a flexible, endless belt, having upper and lower plate holding bands and 55 spaced transverse plate spacing members secured at their ends to said upper and lower bands, said bands and spacing members providing grooves to receive the edge portions of character displaying plates, and flexible character display- 60 ing plates removably held in the grooves and disposed in the spaces formed by the bands and plate spacing members, said plates having opaque surface portions outlining transparent portions which define characters. 65

OTTO W. HARMS.
